US00D942287S

(12) **United States Design Patent** (10) Patent No.: **US D942,287 S**
(45) Date of Patent: **** Feb. 1, 2022**

(54) **SIGNAL DETECTOR**

(71) Applicant: **Jinhe Lan**, Guangdong (CN)

(72) Inventor: **Jinhe Lan**, Guangdong (CN)

(**) Term: **15 Years**

(21) Appl. No.: **29/703,339**

(22) Filed: **Aug. 27, 2019**

(51) LOC (13) Cl. **10-04**

(52) U.S. Cl.

USPC **D10/78**

(58) **Field of Classification Search**

USPC D10/75, 78, 104.1, 65; D14/137

See application file for complete search history.

(57) **CLAIM**

The ornamental design for a signal detector, as shown and described.

DESCRIPTION

FIG. 1 is a front elevational view of a signal detector showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is another perspective view thereof.

The broken lines shown in signal detector form no part of the claimed design.
